UNITED STATES PATENT OFFICE.

BAYARD GUTHRIE, OF PITTSBURG, PENNSYLVANIA, ASSIGNOR OF ONE-HALF TO JOSEPH P. KARCH, OF PITTSBURG, PENNSYLVANIA.

FLYING-MACHINE.

No. 886,122.

Specification of Letters Patent.

Patented April 28, 1908.

Application filed October 31, 1907. Serial No. 400,106.

To all whom it may concern:

Be it known that I, BAYARD GUTHRIE, a citizen of the United States, residing at Pittsburgh, in the county of Allegheny and State of Pennsylvania, have invented certain new and useful Improvements in Flying-Machines, of which the following is a specification.

My invention relates to improvements in the art of aerial navigation and particularly the construction of an air ship or flying machine heavier than air. It will be found, however, that the principles are adapted to balloon suspended or partially suspended machines.

It consists primarily in a ship having on each side one or more rotating members or wheels carrying folding wings simulative of birds' wings in action. Each wheel has several wings,—for instance, four,—so that, as each folding wing passes the position of maximum propulsion effect, it is succeeded by another unfolding wing. A substantially continuous power is thus attained. Each wing is so constructed of resilient ribs and canvas or other flexible fabric that the outward and downward movement, as the wing rotates and unfolds, causes a forward as well as a lifting effect. An aeroplane is preferably employed to aid in sustaining the machine and in soaring or gliding. Suitable rudders or other steering devices are also provided.

In the accompanying three sheets of drawings illustrating one type of the invention, Figure 1 is a perspective view of the machine or ship in flight. Fig. 2 is a plan view of a wheel with one wing extended or unfolded and the opposite wing folded. The intermediate wing is omitted and parts broken away and parts in section to illustrate the construction better. Fig. 3 is a front view of a wheel with one wing extended as in Fig. 2 and parts shown in section. Fig. 4 is a sectional front view of a part of a wheel. Figs. 5 and 6 are detail perspective views of the cams for controlling the opening and closing movements of the wings of a wheel.

The body or hull 1, is of suitable construction and has an aeroplane 2, and a suitable steering device or rudder 3. On each side of the ship is one (or more) wheels such as 4 and 5 which are rotated in opposite directions by any suitable motive power, controlled as desired. Inasmuch as all movement is relative, the moving parts will be described as

though the body of the machine were stationary. Each wheel is mounted on a fixed shaft 6, which extends longitudinally of the ship's body. The wheel frame consists of heads 7 and 8, connected by pairs of bearing plates such as 9, 10, 11 and 12. All the parts of the wheel are carried by this frame and rotate about the fixed shaft as an axis, being driven by suitable means, for instance, by a belt on the pulley 13, which is secured to the rear head 7. Each wheel has four wings adapted to fold and unfold automatically as the wheel rotates. The wings proper each consist of levers, links and ribs with a suitable covering, such as the canvas 14. Considering the extended wings shown in Figs. 2 and 3, the double wing-lever 15 and the double wing-rocker 16 are pivoted in the frame plates 9, 9 and connected by the double wing-link 17. The double rib-lever 18 is pivoted at 19 and connected to the wing-rocker by the rib-link 20. The ribs 21, 22, 23 and 24, as shown, are all formed of leaf springs so that they are stiff at the axis of support 25, and become more and more resilient toward their tips or posterior free ends. The tips are connected by a cord, wire or rope 26 secured at 27 which determines their spacing when opened out. The rib 21 is fixed to the lower member of the rib lever 18 and has an extension plate 28 which serves to gather in all the pivoted ends, 22, 23 and 24 as the wing is folded, until they strike the top 29, as shown at the left in Fig. 2.

The folding and extension of the wings is accomplished automatically as before mentioned. Fixed on the stationary shaft 6, inside the wheel frame, are two cams 30 and 31, shown in Figs. 2, 5 and 6. Cross pieces 33, 33 and 34, 34 carry pairs of plates such as 35, 35 (see Fig. 4). Each pair of the latter is secured to a plate such as 36, and the plates 36, 36 are secured to centering blocks 37, 37 which are free on shaft 6. These cross pieces, plates and blocks constitute part of the wheel frame and support four reciprocal draw bars such as 38, one for each wing. On opposite ends of the draw bars are rollers 39, 39 or other anti-friction devices which coact with the cams 30 and 31 as the wheel rotates, so that the bars reciprocate according to the shape of the cams. In each bar is a recess or opening such as 40 into which projects the short arm of a primary lever 41 11

carrying a roller 42. The other arm of this lever 41 is connected by link 43 to the middle arm of a three-armed lever 44. The other two arms of lever 44 are connected by links 45 and 46 to wing-lever 15 and rocker 16 respectively. Reciprocation of the draw bar 38 is thus transformed into movement of the link and lever connections of the wing, so that the wing is folded and extended alternately as the draw bar is moved forward and aft respectively.

In operation as the outer wings sweep down the tips of the spring ribs and the rear edges of the coverings yield upwardly, so that a forward pressure is exerted. As the wheel rotates and the outer wings begin to fold up, the upper wings are brought toward the outer positions and begin to open out when about 45 degrees from the vertical position, while the preceding wings fold up about 45 degrees below the horizontal position. A substantially continuous pressure is thus exerted so that the movement of the machine is steady and continuous.

25. It will be understood that changes in details of construction may be made and parts omitted or added without departing from the spirit or scope of the claims.

What I claim is:—

30. 1. In a flying machine, a pair of oppositely disposed rotatable wheels arranged with their axes longitudinal of the machine, a plurality of folding wings carried by the wheels and arranged to fold radially and toward the rear, and means for extending and folding said wings successively in planes radial to the axes of the wheels.

40. 2. In a flying machine, a body, an aeroplane secured thereto, means for steering the machine, and a pair of oppositely disposed rotating propelling wings with posteriorly yielding ribs.

45. 3. In a flying machine, a body, a shaft at each side, a rotating wheel on each shaft having folding wings, including a plurality of ribs substantially rigid at their forward portions but yielding upward at their posterior portions and means for automatically extending said wings forwardly and closing them rearwardly.

50. 4. In a flying machine, an aeroplane and oppositely disposed rotating series of radially extensible and contractible wings yielding upwardly at their posterior portions, whereby on a downward movement a propulsive effort is obtained.

5. In a flying machine, a rotating wheel, including folding wings, a reciprocating bar connected to each wing and means for successively operating said bars.

60. 6. In a flying machine, a wheel frame, a plurality of folding wings carried thereby and means for successively closing said wings inside said frame and opening said wings laterally of said frame.

65. 7. In a flying machine, a propelling wing comprising a pivoted support, a wing rocker and a wing lever pivoted to said support, a rib lever connected to said wing lever and to said rocker and a plurality of ribs connected to said rib lever.

70. 8. In a flying machine, a propelling wing comprising a pivoted support, a wing rocker and a wing lever pivoted to said support, a rib lever connected to said wing lever and to said rocker and a plurality of ribs connected to said rib lever.

75. 9. In a flying machine, a folding wing mounted to rotate on a horizontal axis, and including a plurality of resilient ribs pivoted on a common axis.

80. 10. In a flying machine, a rotating wheel including a plurality of folding wings, each including a plurality of pivoted ribs, an extension on one rib of each wing adapted to engage the other ribs as the wing is closed and means for opening and closing the wings successively.

85. 11. In a flying machine, a folding wing comprising a main lever and a rocker, a rib lever hinged on said main lever, a main link connecting the rocker with the hinge between the rib lever and the main lever, a rib link connecting the rocker with the rib lever, a plurality of ribs pivoted to said rib lever and means for operating said rocker, levers, and links.

90. 12. In a flying machine, a reciprocating bar, a two armed primary lever having one arm engaging said bar, a three armed lever having one arm connected to the other arm of said primary lever, a wing rocker and a wing lever connected to the other arms of said three armed lever and means of connection between said wing lever and said wing rocker.

95. In testimony whereof I affix my signature in presence of two witnesses.

BAYARD GUTHRIE.
